Patented Nov. 8, 1887.

UNITED STATES PATENT OFFICE.

HENRY J. WAGNER, OF DAYTON, MISSOURI.

CORN-PLANTER.

SPECIFICATION forming part of Letters Patent No. 372,725, dated November 8, 1887.

Application filed July 18, 1887. Serial No. 244,645. (No model.)

To all whom it may concern:

Be it known that I, HENRY J. WAGNER, a citizen of the United States, residing at Dayton, in the county of Cass and State of Missouri, have invented a new and useful Improvement in Corn-Planters, of which the following is a specification.

My invention relates to an improvement in corn-planters; and it consists in the peculiar construction and combination of devices, that will be more fully set forth hereinafter, and particularly pointed out in the claims.

In the accompanying drawings, Figure 1 is a side elevation of a corn-planter embodying my improvements. Fig. 2 is a top plan view of the same, partly broken away. Fig. 3 is a vertical longitudinal sectional view taken on the line *x x* of Fig. 2. Fig. 4 is a detached perspective view of a portion of one of the main wheels. Fig. 5 is a similar view of one of the seed-dropping devices. Fig. 6 is a vertical sectional view taken on the line *z z* of Fig. 5. Fig. 7 is a horizontal transverse sectional view taken on the line *a a* of Fig. 6, looking upward. Fig. 8 is a sectional view on line *b b* of Fig. 4. Fig. 9 is a top edge view of a portion of one of the runners, showing the offset plate on one side thereof.

A represents the main frame of the machine, which comprises the parallel side bars, *B*, and the cross-bar *C*, extending through the front ends of bars *B* and connecting the same together. The ends of the bars *C* project beyond the outer sides of the bars *B* and form spindles, as shown.

D represents the tongue, which has its rear end pivoted to the cross-bar *C* by means of diverging arms *E*. The center of the cross-bar is enlarged and is provided with a vertical opening.

F represents a platform of suitable size and shape, which is secured on the frame *A*. To the rear ends of the bars *B* are attached brackets *G*, having curved depending arms provided with curved slots *H*.

I represents a transverse shaft or axle, which extends through the said slots, is adapted to move vertically therein, and is prevented from moving endwise by means of collars *K*. To one end of the shaft is rigidly attached a wheel,

F', and to the opposite end thereof is loosely mounted a wheel, *M*.

N represents a clutch which is feathered on the shaft *I*, and is adapted to slide longitudinally thereon and to engage the inner end of 55 the hub of wheel *M*, and thereby lock the said wheel to the shaft.

O represents a hand-lever, which is fulcrumed in an opening in the platform *F*, and has its lower end bifurcated to form arms *P*, 60 that engage an annular groove in the sliding clutch. This hand-lever extends upward from the platform for a suitable height, and is within easy reach of the driver mounted on the seat *R*.

S represents a transverse shaft, which is 65 journaled in blocks *T*, that are provided with vertical arms *U*. The said arms fit in vertical guideways *V*, formed on the rear sides of the vertical arms of the brackets *G*. A crank, *W*, is made at each end of the shaft *S*, the said 70 cranks being in line with each other.

Y represents a rock-shaft, which is journaled transversely on the platform *F*, near the rear end thereof. From said rock-shaft projects rearward-extending arms *Z*, and to one 75 end of the rock-shaft is attached a hand-lever, *A'*.

B' represents a pair of rods which connect the free ends of the arms *Z* to the shaft *S*. By this construction the shaft *S* is adapted to be 80 raised or lowered by means of the hand-lever *A'*, as will be readily understood.

*B*² represents a pair of curved runners, which have their front ends pivoted on the ends of the bars *C*, the rear ends of the said runners 85 being thereby free to move up and down. The rear ends of the runners are provided on their upper sides with vertical extension-plates *C'*, and to the inner sides of the said extension-plates are rigidly secured cylindrical hoppers 90 *D'*, which are provided in one side with a *V*-shaped incised offset or shoulder, *E'*, which extends toward the center of the hopper. The bottom of each hopper is formed by a circular seed-plate, *F'*, having a series of seed cups or openings, *G'*, arranged near its outer edge, and radial projecting spurs *H'*, which extend from the periphery of the seed-plate and are arranged between the cups or openings *G'*.

I' represents a plate which is arranged under each seed-plate. The said plate I' is rigidly secured to the vertical rod K', on which the seed-plate is journaled, and the upper end 5 of which rod extends upward in the center of the hopper and is rigidly attached to the apex of the offset E'. The said rod extends below the plate I' for a suitable distance, and has its lower end bent at right angles to form a horizontal supporting arm, L', on the outer end of which is secured a horizontal semicircular plate, M'.

N' represents vertical cylindrical tubes, one of which is journaled under each bottom plate, 15 I', and the lower ends of the said tubes bear upon the upper sides of the plates M'. These tubes N' are each divided into three vertical channels, O', by means of vertical radial partition-plates P', with which the said tubes are 20 provided. The upper end of each tube N' is provided with a series of three radial projecting spurs, R', which are arranged in the paths of depending tappet pins or studs S' on the under side of the plate F', with one of which 25 each of the spurs H' is provided.

To the inner sides of the runners, at the rear ends thereof, are secured offset plates T', thereby forming spaces of suitable width between the said plates and the inner sides of the runners. The front ends of the said plates are 30 extended obliquely to the runners, and are also inclined rearwardly, as shown, thereby adapting the plates to open furrows in the soil as the machine advances. The seed-tubes N' 35 have their lower ends arranged in the spaces between the plates T' and the runners.

U' represents downwardly-extending arms, one of which projects from the rear side of each hopper. The rear ends of the said arms 40 are bent outward, and are arranged obliquely with relation to the line of draft to form spindles V', on which are journaled circular covering-disks W'. Owing to the inclination of the spindles, the said covering-disks extend 45 obliquely across the furrows, and are thereby adapted to cover the said furrows as the machine advances. Coil-springs X' are placed on the spindles V' and bear against the inner sides of the covering-disks. The said springs 50 serve to normally keep the covering-disks at the outer ends of the spindles, but permit the said disks to slide inward on the spindles when they encounter obstruction, thereby preventing the danger of the disks or their supporting-arms being broken. The extension-plates 55 C' of the runners are provided with horizontal slots or openings, through which the spurs of the rotating seed-disks successively project, for the purpose to be hereinafter explained.

Each wheel F' and M is provided with a rim having its face beveled on opposite sides, thereby adapting the wheels to cut through clods and loose earth and enabling them to obtain a 60 firm bearing on the ground over which they pass, and adapting the wheels to direct the machine in a straight line. From opposite

sides of the rims of the wheels, at suitable regular distances apart, project studs or pins Y'.

Z' represents a concentric ring with which 70 each wheel is provided. The inner edges of the said rings project laterally from the inner sides of the wheels and extend to within a slight distance of the straight outer sides of the runners. These rings are secured to the 75 spokes, as shown.

A' represents a series of tappet-rods with which each wheel is provided, a suitable number of the said tappet-rods being provided for each wheel and the said rods being arranged 80 at suitable regular distances apart. The outer ends of these tappet-rods are passed through openings near the inner edges of the rings Z', and are secured by means of nuts, as shown. The inner ends of the said tappet-rods are bent 85 outward at right angles and bifurcated to form hook-arms B', which pass on opposite sides of the adjacent spokes and engage the inner sides of inner concentric brace-rings, C', with which the wheels are provided.

D' represents U-shaped yokes, which have 90 their arms attached to spokes of the wheels at suitable regular distances apart and coincident with the tappet-rods A'.

F' represents markers, which comprise bolts 95 or pins having their outer ends extending through openings in the outer arms of the frame D' and their inner ends reduced in diameter and extended through openings in the inner arms of the said frame. Coiled springs 100 G' are placed on the reduced portions of the markers and bear between the inner arms of the frame D' and the shoulders on the markers, the said springs thereby serving to normally project the outer ends of the markers 105 radially from the frames D'. The outer ends of the said markers are beveled, as shown, and thereby the markers are adapted to successively enter the soil as the wheels rotate and make openings in the soil along the side and 110 in line with the hills as the seeds are planted, thus enabling the exact site of each hill to be determined, and also enabling the driver to direct his team so that the corn will be planted 115 in exactly parallel rows.

Through each runner B', at a suitable distance from the front ends thereof, extends a transverse shaft, H'. The outer ends of the said shafts are bent rearward at an angle of 120 about thirty-five degrees, and are provided with depending fingers I'. The inner ends of the said shafts are journaled in sleeves K'. Rods L' extend from the said sleeves to the cross-bar C. The inner fingers, I', of each shaft are provided with rearward-extending plates 125 M'. The upper edges of the said plates are provided with inwardly-extending arms N', which are rigidly attached to the rear ends of levers O', that are journaled on the shafts H' and bear against the inner sides of the runners.

P' represents link-rods, which have their upper ends bent at right angles to form arms or spindles journaled in bearings R' on the

lower side of the platform. The lower ends of the said link-rods are also bent at right angles, and are journaled in openings in the front ends of levers O^2 .

5 S^2 represents volute springs, which have their inner ends attached to the lower spindles of the link rods and their outer ends bearing on the rear ends of levers O^2 , the function of these springs being to turn the shafts H^2 , so 10 as to cause the fingers I^2 to normally assume a vertical position.

It will be observed by reference to Fig. 2 that the fingers I^2 are arranged directly in advance of the wheels F' and M , and thereby the 15 said fingers are adapted to clear away stones, clods, and trash in advance of the wheels, thus enabling the said wheels to always keep to the earth, and consequently preventing them from moving faster or slower while passing over ob- 20 structions.

When the lever A' is moved forward, the rock-shaft S is elevated and caused to raise the rear ends of the runners and the covering-disks from the ground, as will be readily understood. As the said runners rise the link-rods P^2 depress the front ends of the levers O^2 , and consequently elevate the rear ends of the 25 said levers, and as the plates M^2 of the fingers are connected to the said levers the said fin- 30 gers are turned rearward, and thereby raised from the earth.

The operation of the planting mechanism is as follows: As the machine advances, the 35 wheels F' and M rotate and the tappet-arms on the said wheels successively engage the projecting spurs of the seed-disks, and consequently rotate the said disks, so that the seeds are dropped therefrom into the tubes N' and onto the plates M' . As the seed-disks rotate 40 rotary motion is imparted to the seed-tubes, and the vertical partitions therein sweep the seeds previously dropped on the plates M' into the furrows, where they are covered by the covering-disks, as before described.

45 It will be understood that the seed-disks are only actuated at the times when the tappet-arms of the wheel are in contact with the spurs of the seed-disks, and therefore by providing the wheel with the requisite number of tappets 50 the hills may be planted any desired distance apart. When one of the tappet-arms is provided for each spoke, the hills of seed or corn will be planted so close together as to form drills.

55 T^2 represents a transverse rock-shaft, which is journaled on the platform F , and has its ends bent at right angles to form arms U^2 , which are curved around the treads of the wheels and are adapted to be engaged by the 60 studs or pins Y' when the rock-shaft is turned rearward, so as to check the rotation of its wheels, and thereby preventing the seeding mechanisms from operating while the machine is being ranged at the ends of the rows.

65 V^2 represents a pedal with which the shaft T^2 is provided, and from the upper side of the said shaft projects an arm, W^2 . A vertical

standard, X^2 , rises from the upper side of the platform near one side thereof, and to the upper end of the said standard is fulcrumed a bell-crank lever, Y^2 . The front arm of this lever is provided at its free end with an open slot, Z^2 , that engages the upper end of arm W^2 , and the rearward-extending arm of the said bell-crank lever extends on the inner 75 side of the hand-lever O , and is adapted to be engaged by the same.

When the lever O is moved inward so as to cause the clutch to engage the wheel M , the said lever strikes the rear arm of the bell-crank 80 lever, and consequently turns the latter to cause the same to tilt the rock-shaft T^2 forward, and thereby disengage the arms of the said shaft from the rims of the wheel.

When it is desired to use the machine for 85 planting corn in check-rows, the operation thereof is as follows: When the machine is arranged at one side of the field, the lever O is moved to cause the clutch to engage the wheel M , and the wheels F' and M are provided with 90 only a few (preferably three) tappet rods or markers each, as shown in Fig. 1, and the wheel M is locked to the shaft with its tappet-arms and markers arranged directly in line with these of the wheel F' . The machine is 95 then started, and the wheels, being both locked to the main shaft, are caused to rotate in unison, and thereby plant the seeds in hills which are in line with each other. When the machine reaches the opposite side of the field, it 100 is turned and arranged in position parallel with the planted hill, and the driver depresses the pedal V^2 with one foot, thereby turning shaft T^2 rearward, so that its arms bear against opposite sides of the rims of the wheels and 105 prevent the wheels from rotating when the studs or pins Y' thereof come in contact with the said arms. These studs or pins are so arranged that when they engage the arms of the 110 brake-shaft the planting mechanism is in position ready to drop corn into the furrows. The planter is then moved forward, causing the runners to be crowded or forced into the ground, and when the machine is in position and the dropping mechanism is exactly in 115 line with the hills previously planted the operator releases the shaft or brake T^2 from the 120 wheels and moves the lever O so as to lock the wheel M to the main shaft, and the operation before described is then repeated.

A^3 represents a short transverse axle, which is secured to the lower end of a vertical pivotal bolt, B^4 , which extends through the vertical central opening in the cross-bar C . On the ends of the said axle are journaled small 125 wheels C^3 , which serve to support the front end of the frame, and thereby relieve the necks of the horses. The pivotal bolt and its wheels and axle form a guiding and supporting truck for the planting-machine, as will be readily 130 understood.

The function of the curved brackets G is to allow the wheels F' and M to remain on the ground and not lose their measurement when

the runners might be lifted up by clods or trash.

I have herein described my invention as a corn-planter; but it will be readily understood 5 that it is adapted for planting sorghum, beans, peas, and other seeds with equal facility.

Having thus described my invention, I claim—

1. In a planter, the combination of the hopper, the rotating seed disk or plate F² therein, having the depending tappets S', and the depending revoluble tube arranged under the discharge-opening of the hopper, and having the spurs R' engaged by the tappets S', substantially as described. 15

2. The combination, in a planter, of the frame, the wheels having the tappet-arms A², the hoppers having the seed plates or disks provided with the spurs adapted to be successively operated by the tappet-arms, said spurs having depending tappets S', and the depending revoluble tube arranged under the discharge-opening of the hopper, and having the spurs R' engaged by the tappets S', substantially as described. 25

3. The combination, in a planter, of the frame, the wheels having the tappets A², the runners having their front ends pivoted to the frame, the hoppers secured to the said runners and having the seed disks or plates provided with the spurs engaged by the tappets A², and having the depending tappets S', the depending revoluble tubes arranged under the discharge-opening of the hopper, and having the spurs R' engaged by the tappets S', and the lever to raise and lower the runners, for the purpose set forth, substantially as described. 30

4. The combination, in a planter, of the hopper having the rotating seed-disks, the depending revoluble tube arranged under the discharge-opening of the hopper and provided with the vertical channels, the said tube being connected to and actuated by the seed-disk as the latter rotates, and the stationary plate M', arranged under the lower end of the tube, substantially as described. 45

5. The combination, in a corn-planter, of the wheels F' and M, the vertically-movable runners having the furrow-openers and arranged 50 beside the wheels, the fingers or guards attached to the said runners and arranged in front of the wheels, for the purpose set forth, and the lever to raise and lower the runners, substantially as described.

55 6. The combination, in a planter, of the vertically-movable runners arranged along the sides of the operating-wheels, the shafts H², journaled to the said runners and having the

depending arms I² at their outer ends, the said shafts being provided with the lever-arms O², 60 and the links connecting the said lever-arms to a fixed point, whereby the fingers I² will be turned rearward when the runners are raised, substantially as described.

7. The combination, in a corn-planter, of the 65 runners, the shafts H², journaled thereto and having the guard-fingers I², and the lever-arm O², and the volute springs connected to the said lever-arms, for the purpose set forth, substantially as described. 70

8. The combination, in a planter, of the frame, the wheels having the tappets A², the runners having their front ends pivoted to the frame, the hoppers secured to the said runners and having the revoluble seed-disks provided 75 with spurs adapted to be engaged by the tappets A², the furrow-openers attached to the runners, the obliquely-arranged spindles attached to the runners in rear of the furrow-openers, the obliquely-arranged circular covering-disks journaled on the said spindles, and the lever to raise and lower the runners, substantially as described. 80

9. In a planter, the wheels having the concentric rings Z' and C⁴ attached to the spokes, 85 and the tappet-arms having their outer ends attached to the rings Z' and their inner ends bifurcated to form hook-arms adapted to pass on opposite sides of the spokes and engage the inner rings, substantially as described. 90

10. In a planter, the combination of the furrow-openers, the planting mechanism to drop seed into the furrows, the obliquely-arranged spindles in rear of the furrow-openers, the obliquely-arranged circular covering-disks journaled on the said spindles, and the springs bearing against the said covering-disks, substantially as described. 95

11. The combination, in a check-row corn-planter, of the main shaft, the wheel F', rigidly secured thereto, the loose wheel M on the said shaft, the clutch to lock the said wheel to the said shaft, the lever O, connected to the said clutch to operate the same, the rock-shaft T², having the brake apparatus, and the arm W², 100 and the bell-crank lever Y², connected to the arm W² and bearing against the lever O, substantially as described.

In testimony that I claim the foregoing as my own I have hereto affixed my signature in 110 presence of two witnesses.

HENRY J. WAGNER.
